UNITED STATES PATENT OFFICE.

JOHN P. WEIS, OF BROOKLYN, NEW YORK, ASSIGNOR, BY MESNE ASSIGNMENTS, TO METROPOLITAN SEWING MACHINE COMPANY, A CORPORATION OF NEW YORK.

SEWING-MACHINE.

No. 921,188.

Specification of Letters Patent.

Patented May 11, 1909.

Application filed June 5, 1903. Serial No. 160,207.

To all whom it may concern:

Be it known that I, JOHN P. WEIS, a citizen of the United States, residing in Brooklyn, county of Kings, and State of New York, have invented a new and useful Improvement in Sewing-Machines, of which the following is a description.

This invention relates to sewing machines of the chain-stitch type, and more particularly to machines of the class mentioned for overseaming purposes.

An object of my invention is to produce a light and rapid running machine and one wherein all the operating parts are of the simplest character and conduce to ease, rapidity and perfection of operation.

Another object of my invention is to provide an overedging machine having very few and simple parts, and one wherein all objectionable and unnecessary parts are eliminated, thus conducing to simplicity and strength.

With the above objects in view and others which will hereafter appear in this description my invention consists in the parts, features, elements and combinations herein-after described and claimed.

In the drawings: Figure 1 is a front elevation of so much of a sewing machine as is necessary to illustrate the parts and features of my invention; Fig. 2 is a top plan illustrating the connection between the looper-rod and the spreader-carrier; Fig. 3 is a section on the line 12—12 of Fig. 2; Fig. 4 is a section on the line 13—13 of Fig. 1; Fig. 5 is a top plan of the supporting-bracket for the looper-carrier showing the latter in horizontal section; and Fig. 6 is a section on the line 15—15 of Fig. 1.

The frame of the machine is indicated by 1, the driving-shaft by 2, which carries at its outer end the usual driving-pulley and hand-wheel. Adjacent the pulley is the eccentric 3, surrounded by the strap 4, pivotally connected at its upper end to the needle-bar actuating lever 5, pivoted to the frame of the machine at 6, having the depending arm 7, and the overhanging arm 8, connected by a link 9, to a suitable sleeve 10, clamped to the needle-bar 11, carrying at its lower end the needle 12, by means of the needle-clamp hereafter described. The arm 8, of the lever

5, is provided with a number of perforations 13, the object of which is to remove therefrom a great deal of the material of said 55 arm, thus relieving the same of considerable of its weight and rendering the same exceedingly light. The rest of the lever 5, may be likewise treated for the same purpose.

The link 9, is connected to the arm 8, and 60 sleeve 10, by means of hollow journal-pins 9*, such construction admitting the insertion of oil in the said pins for lubricating purposes; and it has been found in practice that the oil thus contained in the pins will not fly 65 out, but will slowly overflow the end of the pins, creep along the outside of the latter and gradually and effectually lubricate the journals, this being due to capillary attraction. Usually two links 9, are employed and 70 the journal-pins are clamped and held at 9*, by the usual form of split-clamp, the links being on opposite sides of and embracing said clamps.

The arm 7, of the lever 5, is provided at its 75 lower end with a supporting-screw 7*, which is rigidly held in said arm in any suitable manner, by means of which the holder for the looper-rod is connected thereto. Said holder 14, consists of the split clamp, the 80 parts of which are adjustable so that the clamp may be freely held on the shank of the screw 7*, by means of the screw 15 passing through the split portions of the clamp; and the extension 16, is provided with a 85 groove 17, in which is seated one end of the looper-rod 18, and held by the screw 19. This connection is simple, effective and cheap, and provides a ready means for connection and adjustment so that the clamp 90 may work easily on the screw and be adjusted thereon to the proper extent. From this construction it will be apparent that the split portion of the angular clamp or holder 14 can be adjustably set upon the shank of 95 screw 7*, by means of the clamping-screw 15; that is to say, by loosening the screw 15, the angular holder or clamp may be given the desired freedom of movement on the screw 7*, relatively to the depending supporting-arm or extension 7 of the lever 5, the movement being on and around the screw 7*. This enables wear to be taken up, variations in the screw to be compensated for, and al-

lows the clamp or holder 14 to assume any proper angle relatively to the looper-carrier in assembling the parts or during the operation of the machine, so that the connecting-rod 18 may be properly directed toward and for conuection with the looper-carrier. The clamp or holder 20 at the other end of the connecting-rod 18 being of similar character, may be likewise connected to the looper-carrier for like purposes. The connecting-rod 18, as previously described, may also be adjusted lengthwise of the extension 16 of the clamp or holder 14 for obvious reasons, by providing said rod with a longitudinal slot 18^a through which the screw 19 works, and the two adjusting and connecting means just described obviously also render the clamp 14 and rod 18 relatively adjustable while on the machine.

The looper-rod 18, is substantially rectangular in cross section,—see Fig. 3,—and is provided longitudinally with a rib 18^b, formed by depressing the metal thereof so as to convex the same. This construction renders the looper-rod exceedingly light and strong, the bead or flange 18^b, lending strength to the rod, overcoming longitudinal bending or flexing thereof, and preventing vibration. At its forward end the looper-rod 18, is connected by means of a clamp 20, to the looper-carrier, said clamp, and its connection with the rod and with the carrier, being in all material respects substantially the same as the clamp 14. The looper-carrier 21, is provided at its upper end with the socket 22, in which is suitably clamped the looper 23. The looper-carrier 21, has fixed thereto at its lower end, a short - shaft or journal 24, by means of a clamping screw 25. The shaft 24, has its bearings at opposite ends in the sleeves 26, which are clamped, respectively, in the brackets 27, formed upon the slide 28, dovetailed into the bed-plate of the frame. The brackets 27, are in the form of split clamps and securely bind the sleeves 26, by means of the screws 29. The slide is adjustable in the bed-plate, and is held in any desired position by means of the screw 30, extending therethrough and bearing upon the bed-plate, so as to force the inclined edges 28^c, of the slide against the complementary portions of the bed-plate. This enables the looper carrier 21, to be properly and accurately adjusted relatively to the needle.

A bracket 31, is suitably secured to the bed-plate by means of screws 32, and is provided with a split standard 33, in which is clamped the hollow pin 34, by means of the screw 35. Links 36, are supported upon the pin 34, embrace the standard 33, and at their upper ends are connected to the hollow pin 37, and embrace the spreader carrier 38, in which the said pin 37, is suitably clamped by means of the screw 39, the said carrier 38,

being split for the purpose. The pins 34, 65 and 37, and their journals and bearings, are lubricated in the saime manner as described above in connection with the pins 9^c. At its forward end the spreader-carrier 38, is provided with a clamp-socket 40, in which the stem of the spreader 41, is clamped by means of the screw 42. The rear end of the spreader-carrier is provided with an enlargement 43, circular in form affording a bearing-socket for the reception of a ball 44, bored diametrically for the reception of a pin 45, which slides freely in said ball. The carrier 38, within and on opposite sides of its enlargement 43, is provided with journal-bearings 46, the ends of which are depressed 80 correspondingly to the surface of the ball, and engage the latter and afford bearings therefor. The pin 45, is fixed by means of the screw 47, to the clamp member 48, which embraces the looper-rod 18, said member 85 having the overhanging lip 49, and the beveled flange 50, for the purpose. A clamp-plate or block 51, having its inner face made in the form of a truncated pyramid, engages the lower edge of the looper-rod and 90 the beveled flange 50, of the member 48, and is securely held in place by means of the screw 52, passing through said block 51, and screwing into the member 48. This construction of clamp, as will be obvious, 95 securely binds the members thereof to the looper rod and prevents any movement of the parts relatively, the beveled flange 50, and the corresponding face of the member 51, enabling the latter to be wedged tightly 100 against the lower edge of the rod 18, and force its upper edge under the lip 49. Moreover, the connection between the looper-rod and spreader-carrier is, by this construction, 105 simple, strong and effective, and makes an easy and light running medium for the transmission of power from the looper-rod to the spreader-carrier.

The spreader 41, has the U-shaped shank, one arm of which is held in the socket 40 110 of the carrier 38. The body of the spreader is connected to, or formed in continuity with, the other arm of the shank, is properly curved, and extends therefrom at substantially a right-angle. The body of the spreader 115 may be provided with the usual eyes and thread-groove for properly carrying a thread. This form of spreader has been found exceedingly useful and important in that it can be passed through a very small opening in the cloth-plate, and can also be used in operating upon lace edgings and open-work, because it can be passed between the bars and meshes thereof without catching and lay an ornamental inner edging in 120 like manner as upon the extreme edge of other fabrics.

A needle-clamp 55, secured to the end of

the bar 11, carries the needle 12, this clamp being of the form shown in my patent granted March 2, 1909.

From the above construction of the parts 5 of my machine it will be clear that I have provided a light running machine, capable of attaining very high speed, because by making the needle-lever light, as above described, and rendering the looper-rod light 10 and strong, the inertia of heavy parts, heretofore employed in sewing machines of this class, does not have to be contended with nor taken into consideration in the construction 15 and operation of the machine. Moreover, by making the journal pins 9, 34, and 37, hollow as described, the machine is thoroughly lubricated at points where the wear and friction are greatest. Thus the wear and strain on the connection between the eccentric 20 3, and strap 4, and the latter and the needle-lever, are quite materially reduced and overcome, it being well known in the art that these points are exceedingly weak and most likely to snap and break.

25 It will further be seen that, by the connection provided between the looper-rod and the spreader-carrier, several desirable results are obtained. For example, the rocking of the carrier over its fulcrum has a tendency 30 to cause the connection between the same and the looper-rod to vibrate excessively, and when a circular looper-rod is used such vibration cannot be overcome. This vibration at the connection multiplies exceedingly 35 at the point of the spreader, causing excessive side movement of the latter and resulting in preventing the needle from properly cooperating with the spreader and its thread. By my construction the vibration 40 of the connection between the spreader-carrier and the looper-rod is reduced to a minimum, and substantially no side movement or vibration occurs at the point of the spreader. These are important functions in this class 45 of machines, and especially in operating upon lace or open-work fabrics.

Having thus described my invention what I claim and desire to secure by Letters Patent is:

50 1. A sewing machine comprising a spreader and a spreader-carrier, a bracket for supporting said carrier, a pivotal connection between said bracket and carrier including a link and hollow journal pins connecting said link with said bracket and carrier respectively.

2. In combination, a looper and a looper-carrier, a spreader and a spreader-carrier, actuating means therefor including a connection between the two carriers comprising 55 a pin fixed to one part, a socket fixed to another part, and a ball in the socket having a loose sliding connection with the pin.

3. In combination, a looper and a looper-carrier, a spreader and a spreader-carrier,

actuating means therefor including a clamp, one portion of which is provided with an overhanging lip and a beveled extension and another portion of which is substantially in the form of a truncated pyramid, and means 70 for holding the two parts together.

4. In combination, a looper and a looper-carrier, a spreader and a spreader-carrier, means for actuating the same, said means including a rod, a clamp secured thereto, and 75 a loose sliding connection between said clamp and the spreader-carrier.

5. In combination, a looper and a looper-carrier, a spreader and a spreader-carrier, means for actuating the same, said means including a rod substantially rectangular in 80 cross-section, a clamp secured thereto, and a loose sliding connection between said clamp and the spreader-carrier.

6. A sewing machine comprising stitch-forming mechanism including in its actuating parts a driving-lever, in combination with a link-connection between said lever and a part of the stitch-forming mechanism, and hollow journal pins connecting the link 85 respectively with said part and said lever.

7. A sewing machine having in combination a looper and a looper-carrier; a driving-lever for actuating the said carrier; a connection between the lever and carrier, including a concavo-convex rod having greater 90 breadth than thickness, and an angular clamp, one portion of which clamp parallels said rod; means for adjustably connecting said portion of the clamp to the rod; and 100 means for adjustably connecting the other portion of the clamp to one of the other of said elements.

8. A sewing machine comprising a looper and a looper-carrier, a bracket for supporting the same, means for adjusting the bracket, a shaft clamped to the carrier, and bearings on the bracket for said shaft.

9. A sewing machine comprising a looper and a looper-carrier, a shaft secured to the 110 carrier, a bracket supporting the shaft, journal sleeves carried by the bracket in which the shaft operates, and means for adjustably clamping the sleeves in the bracket.

10. A sewing machine comprising a 115 looper and a looper-carrier, a shaft adjustably secured to the carrier, a bracket, and means for supporting the shaft in the bracket which permit of a relative adjustment between the two.

11. A sewing machine comprising a spreader and a spreader-carrier, a journal support for said carrier extending on opposite sides thereof between its ends, means for adjustably clamping the journal support in 125 the carrier, means for pivotally supporting said carrier which embraces the latter and engages said support, and means for supporting the spreader on the carrier.

12. A sewing machine comprising a 120 180

spreader and a spreader-carrier, an adjustable journal carried by said carrier and extending transversely thereof on opposite sides, means for supporting said carrier which engages said journal, and a clamp-socket also carried by the spreader-carrier for adjustably supporting a spreader.

In testimony whereof I have hereunto signed my name in the presence of two subscribing witnesses.

JOHN P. WEIS.
